UNITED STATES PATENT OFFICE.

WILLIAM LAWTON, OF HUDDERSFIELD, COUNTY OF YORK, ENGLAND.

DEVICE FOR GUIDING THE SLIVER IN SLIVER-BOXES OF CARDING-ENGINES.

SPECIFICATION forming part of Letters Patent No. 392,275, dated November 6, 1888.

Application filed May 1, 1888. Serial No. 272,495. (No model.) Patented in England January 15, 1887, No. 658.

To all whom it may concern:

Be it known that I, WILLIAM LAWTON, a subject of the Queen of Great Britain, residing at Huddersfield, in the county of York, 5 England, have invented certain new and useful Improvements in Devices for Guiding the Sliver in Sliver-Boxes of Carding-Engines, (which are the subject of Letters Patent of Great Britain, No. 658, dated January 15, 10 1887,) of which the following is a specification.

This invention relates to sliver-boxes which are used in carding-engines for receiving the sliver as it leaves the doffing-rollers and conveying it away.

15 Sliver-boxes as heretofore made consist of a long box placed parallel with and beside the doffer and just below the doffing-comb. Through this box an endless belt runs, onto which the sliver falls as it is removed from the 20 doffer by the doffing-comb. This belt has usually conveyed the sliver to one side of the carding-engine, from whence it was removed. In falling on this belt, and while being carried along the box, the sliver was apt to catch in 25 the sides of the belt or the corners of the box, thereby breaking or injuring the sliver.

The object of my invention is to prevent the catching or breaking of the sliver in the sliver-box and to deliver it from the endless belt in 30 a more compact and concentrated form than heretofore.

To this end in carrying out my invention I employ means for keeping the sliver in the center of the sliver-box and the endless belt, 35 consisting of oscillating or reciprocating guide or push plates which work against the sliver on the endless belt and gradually force it into compact form near the center of the belt.

In the accompanying drawings, Figure 1 is 40 a fragmentary perspective view, partly in section, of a carding-engine having my improvements applied thereto. Fig. 2 is a fragmentary side elevation thereof, partly in section. Fig. 3 is a fragmentary plan thereof, and Fig. 4 is 45 a fragmentary vertical section cut on line 4-4 in Fig. 3. Fig. 5 is a fragmentary plan of a sliver-box, illustrating a modified form of my invention.

Let A represent the frame of the carding- 50 engine, and B the carding-cylinder.

b is the doffer, and c the doffing-comb, which

is actuated by a vertical rod, d, from a crank, e, situated below the doffer and driven from any suitable part of the carding-engine.

f is the sliver-box, and g is the endless belt 55 traveling through the box. This belt g plays over pulleys g', mounted at each end of the sliver-box f. (Only one of these pulleys is shown in the drawings.) Two nipping-rollers, h h, mounted over the belt g and roller g', receive the sliver from a funnel-shaped mouth-piece, h', over the belt g and conduct the sliver away. To drive the belt g and the nipping-rollers h h, the shaft carrying the pulley g' is 60 extended along the frame of the engine, and is provided with a bevel-gear, a, which meshes with an idler or intermediate pinion, a', driven by a spur-gear, b', mounted on the end of the shaft of the doffer b. A spur-gear is fixed on the shaft of the pulley g, and meshes with a 65 similar gear on the shaft of the lower nipping-roller h. This latter gear meshes with another on the shaft of the upper nipping-roller h. Thus upon the rotation of the spur-gear b' the belt g and nipping-rollers h are caused to ro- 70 75 tate.

The parts thus far described are of the ordinary construction now in use on carding-engines.

In applying my invention I provide vertical plates or wings j and k, which work over the belt g in the sliver-box f. The plate j is fastened at one end to the sliver-box at l and projects over the endless belt g angularly. The plate k is preferably fastened at one end to the 80 frame of the carding-engine or to the box f by a pin or stud, m, and projects over the belt g toward the plate j. These plates are mounted so that their free ends can be oscillated toward and from the center of the belt g. These plates 85 j and k play over the surface of the belt g, and are so arranged that their converging ends play immediately back of the mouth-piece h'. The plates j and k are designed to keep the sliver in the center of the belt g, and to gradually work the sliver into this position on the belt the plates are oscillated toward and from each other. For oscillating the plates j and k, I connect them, through the medium of slides p p' and connecting-rods n and o, with 90 eccentrics s and t, respectively. The plates j and k are connected to the slides p and p' by 95

means of arms or pins q' , projecting down from the slides and engaging the free ends of the plates. These plates travel in a track or slide-way, q , which is mounted on a bracket, p^2 , bolted to the frame Λ of the carding-machine. This slideway q extends over and across the sliver-box f , just behind the nipping-rollers h , and it supports the mouth-piece h' by ties q^2 , leading from the slideway down to the mouth-piece. The slideway consists of two parallel horizontal grooved tracks, between which the slides p and p' travel. These slides are retained in the tracks by projections on the sides of the slides, which take into the grooves in the tracks. The free ends of the plates j and k are controlled and supported by the slides p and p' , and I prefer to adjust the connection between the slides and plates so that the bottom edges of the plates will just clear the endless belt g . To accomplish this adjustment, I raise or lower the free ends of the plates j and k relatively to the endless belt g , preferably by means of nuts upon the arms or pins, which project down from the slides p and p' and support the free ends of the plates. The connecting-rod n is fastened to the slide p at one end and to the strap embracing the eccentric at the other. Slide p' is connected in like manner by connecting-rod o with eccentric t . The eccentrics s and t are mounted on a shaft carried in a bracket fastened to the bracket p^2 on the frame Λ of the carding-engine, and this shaft is provided with a pulley, u , carrying a belt, u' , which belt is driven from a pulley on the "fancy" shaft v , or from any other suitable rotating part of the carding-engine. The rotation of the eccentrics s and t causes, through the connecting parts, the oscillation of the plates j and k , and as the eccentrics are placed diametrically opposite each other on the eccentric shaft the free ends of the plates j and k are caused to move alternately toward and from each other over the surface of the belt g .

To prevent any waste from adhering to the nipping-rollers h , and thereby injuring the sliver, I provide the upper edge of the mouth-piece h' with a cover of felt, h^2 , which comes in contact with the lower roller h and rubs off any waste that may adhere to that roller. For cleaning the upper roller h , I provide a bar, w , covered with felt, w' , on its lower side. This bar w is held by its ends in the frame supporting the rollers h , and its lower and felted side rests on the top of the upper nipping-roller h and wipes the adhering waste therefrom as the roller revolves.

In operation the sliver, after passing the ordinary card-flats of the carding-engine, is removed from the carding-cylinder by the doffer b . The doffer carries the sliver over the sliver-box f , when the sliver is removed from the doffer by the dosing-comb c and falls upon the endless traveling belt g in the sliver-box f . The belt g carries the sliver out toward the nipping-rollers h , As the sliver is carried out by the belt g , the oscillating

plates j and k act on the sliver and gradually push or rub it into a compact mass in the central part of the belt, delivering the sliver at 70 their free ends into the mouth-piece h' , which feeds it to the nipping-rollers h through a reduced nozzle. The sliver is carried under and up in front of the lower nipping-roller h and back between the upper and lower nipping-rollers, and is delivered from behind the upper nipping-roller h , from whence it may be conveyed where desired.

In Fig. 5 I have shown a form of my invention, wherein the plate k is stationary, it being fixed to the frame of the carding-engine by two stays. In this figure the plate j is shown as having a lateral reciprocating movement over the surface of the belt g toward and from the plate k . This movement is imparted to it 85 by two pitmen, n n' , which are connected to the plate j at one end and to cranks on the shaft carrying the driving-pulley u at the other end. By this construction the sliver on the belt g is pushed up toward the plate k by the 90 reciprocation of the plate j .

I may make the plates j and k of wood or sheet metal, and the other parts of the carding-engine and sliver-box may be made of any suitable material, such as is commonly used for 95 those machines.

It will be readily understood that various details of my invention may be altered without changing the character of my invention, the construction and operation shown and described being the preferred form in which I use it. For example, the plates j and k may be oscillated by any suitable mechanism instead of the eccentrics shown; also in some machines the plates j and k may be constructed so that one is stationary and the other movable, as shown in Fig. 5. It will also be understood that, instead of the slideway and slides used in oscillating the plates j and k , these plates may be connected directly with the connecting-rods n and o . Nor is it essential that a mouth-piece, h' , be used in connection with my sliver-box. In cases where there is no sliver-box used, and the endless belt alone is relied upon to carry the sliver away from the doffer, my oscillating plates may be used with the same advantage as when used with a sliver-box.

I claim as my invention, in a carding-engine or analogous machine, the following novel features and combinations, substantially as hereinbefore set forth, namely:

1. The combination, with an endless traveling belt, of a laterally-reciprocating plate arranged to move transversely over the surface of said belt and to push the sliver into a compact form on the belt, and means for imparting motion to said plate.

2. The combination, with a sliver-box and the endless traveling belt therein for carrying the sliver, of a laterally-reciprocating plate in the sliver-box arranged to move transversely over the surface of said belt, and means for imparting motion to said plate.

3. The combination, with a sliver-box and the endless traveling belt therein, of a plate fixed at its inner end and free to vibrate laterally at its outer end, and means for imparting motion to said plate.
4. The combination, with a sliver-box and the endless belt for carrying the sliver, of two reciprocating plates mounted over said belt at opposite sides thereof and movable each toward and from the other, and means for imparting motion to said plates.
5. The combination, with a sliver-box and the endless belt for carrying the sliver, of two reciprocating plates mounted over said belt at opposite sides thereof and movable each toward and from the other, and driving-gear for
- moving said plates simultaneously toward and from each other.
6. The combination, with the sliver-box *f* and traveling belt *g*, of oscillating plates *j* and *k*, fixed at their inner ends and free at their outer ends, slides *p* and *p'*, connected to said plates and movable transversely thereof, and a driving-gear for imparting reciprocatory motion to said slides, substantially as set forth. 25

In witness whereof I have hereunto signed my name in the presence of two subscribing witnesses.

WILLIAM LAWTON.
